DISPLAY TERMINAL FOR A COMPUTER OR THE LIKE

Seton Cottier, Woodstock, and John D. March, Newburgh,
N.Y., assignors to International Business Machines Cor-
poration, Armonk, N.Y., a corporation of New York

Filed Jan. 2, 1968, Ser. No. 10,031

Term of patent 14 years

(Cl. D26—5)

FIG. 1

FIG. 2

FIG. 3

FIGURE 1 is a perspective view taken from the front and one side of a display terminal for a computer or the like showing our new design;

FIGURE 2 is a perspective view taken from the rear and side opposite that shown in FIGURE 1; and

FIGURE 3 is a top plan view thereof.

It is to be understood that the keyboard is continuous throughout the area indicated by broken lines in FIGURES 1 and 3.

We claim:

The ornamental design for a display terminal for a computer or the like, substantially as shown and described.
